US00D944234S

(12) **United States Design Patent** (10) **Patent No.:** **US D944,234 S**
(45) **Date of Patent:** **** Feb. 22, 2022**

(54) **DISPLAY MOUNT**

(71) Applicant: **SHENZHEN BESTQI INNOVATION TECHNOLOGY CO., LTD**, Shenzhen (CN)

(72) Inventor: **Jiying Zou**, Shenzhen (CN)

(73) Assignee: **SHENZHEN BESTQI INNOVATION TECHNOLOGY CO., LTD**, Shenzhen (CN)

(**) Term: **15 Years**

(21) Appl. No.: **29/762,307**

(22) Filed: **Dec. 16, 2020**

(51) LOC (13) Cl. **14-03**

(52) U.S. Cl.

USPC **D14/239**

CLAIM

The ornamental design for a display mount, as shown and described.

DESCRIPTION

FIG. 1 is a perspective view of a display mount showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 3.

The broken lines in the drawings depict portions of the display mount that form no part of the claimed design.

1 Claim, 10 Drawing Sheets
